UNITED STATES PATENT OFFICE.

VINCENT BENDIX, OF CHICAGO, ILLINOIS.

ENGINE-STARTER.

1,327,132.

Specification of Letters Patent.

Patented Jan. 6, 1920.

Application filed September 25, 1916. Serial No. 121,952.

To all whom it may concern:

Be it known that I, VINCENT BENDIX, a citizen of the United States, residing at Chicago, in the county of Cook and State of Illinois, have invented certain new and useful Improvements in Engine-Starters, of which the following is a specification.

My invention relates to that type of engine starter exemplified in patents heretofore issued to me, for instance, Patent No. 1,125,935, dated January 26, 1915, and Patent No. 1,172,864, dated February 22, 1916, which starters are characterized by a prime mover such as an electric motor, and a transmission or drive for transmitting the power of the motor by means of a rotatable screw shaft and a pinion mounted thereon, to a member of the engine to be started, such as the fly wheel thereof. This drive comprises a screw shaft operated either directly or indirectly by the motor and the pinion screw-threaded on such shaft and having longitudinal movement thereon and rotary movement therewith.

My invention pertains to a novel and efficient construction of such type of starter whose advantages will be made apparent by the description hereinafter given.

In the drawing Figure 1 is a sectional elevation of an electric starting motor with my transmission or drive applied thereto, some of the parts being shown in elevation; Fig. 2 a section on the line 2-2 of Fig. 1 looking in the direction of the arrows; and Fig. 3 a diagrammatic view of the electrical circuits concerned with my device as shown.

The prime mover is an electric motor here shown more or less diagrammatically at 1 and provided with a hollow armature shaft 2 having bearings 3 and 4 in opposite ends of the motor casing. A rotatable screw-shaft 5 extends axially through the armature shaft and projects at either end thereof, one end being provided with screw threads 5^a on which is mounted a pinion 6. One end of the hollow armature shaft 2 is extended beyond the motor case and its bearings and there provided with a collar 7 here shown as screwed on such extended end of the armature shaft. This collar and consequently the armature shaft is operatively connected with the rotatable screw shaft 5 by a resilient driving connection which is here shown as a coiled spring 8 encircling the

outer extended end of such screw shaft and 55 anchored at one end of the collar 7 by means of the bolt 9 and at its other end to a collar 10 which is pinned to the shaft 5 by means of the bolt or pin 11. By these means the rotary movement of the armature is transmitted by a yielding driving connection to the rotatable screw shaft 5. At the other end of the armature shaft is arranged an adjusting nut or collar 12 screw-threaded upon the screw-shaft just in rear of the screw-threaded portion 5^a, such nut being adapted to assist in retaining the armature shaft in proper position and to take up any possible play between the parts.

The pinion 6 is adapted to mesh with a 70 part of the engine to be started, such as the teeth 13^a of the fly wheel 13. When the electric motor is operated the power is transmitted from the armature shaft through the spring 8 to the rotatable screw shaft 5 with 75 the result that the pinion 6 is caused to automatically travel or advance longitudinally of the screw shaft and inwardly toward the motor into engagement with the fly wheel teeth, to the position shown in the dotted 80 lines. The nut 12 also acts as a stop nut with the result that the pinion cannot travel longitudinally after coming in contact therewith and hence takes up the rotary movement of its screw shaft, thereby turning the 85 fly wheel and starting the engine. When the engine, such as a gas engine, starts on its own power the pinion is automatically demeshed by being moved outwardly longitudinally of the screw shaft and out of mesh 90 with the fly wheel and back to the home position shown in full lines in Fig. 1. The pinion is stopped in this latter position by means of the collar 14 secured to the outer end of the screw shaft by means of the 95 pin 15.

In order to assure the longitudinal movement of the pinion 6 and at the same time provide an automatic switch device, a strap or yoke 16 is adapted to fit in a circular 100 groove 6^a in the pinion. This yoke has a pair of upwardly extending parallel arms 16^a adapted to slide or move along opposite sides of a plate 17 depending from the bracket 18 which is secured to one end of 105 the motor casing. On one side of this plate are arranged the two contact points 19 arranged in the electrical circuit illustrated by

Fig. 3 comprising a portion of the main circuit in which the electrical starting motor is interposed. When the starting switch indicated at 20 is operated the current is supplied to the electric motor through the wires 21 and when the pinion reaches its meshed position with respect to the fly wheel the current is kept supplied to the electric motor through the other set of wires 22 in which the contacts 19 are directly interposed with the result that even though the operator breaks the connection at the starting of the switch or button 20 the current will still be supplied to the starting motor. However, when the pinion is automatically demeshed in the manner already explained the connection is broken at the contacts 19 and the current will be cut off from the electric motor. The fit of the yoke 16 on the pinion is such as to afford some friction which in connection with the inertia of the pinion is sufficient to assure the longitudinal movement of the pinion on the screw shaft under all conditions of service.

25. I claim:

1. In combination with an electric starting motor whose armature shaft is hollow from end to end and power-transmitting means interposed between said armature shaft and a part of the engine to be started, said means including a shaft passing through the armature shaft and at one end operatively connected with such armature shaft and at its other end having a driving member adapted to operatively engage said engine part.
2. In combination with an electric starting motor whose armature shaft is hollow from end to end and power-transmitting means interposed between such armature shaft and a part of the engine to be started, said means including a driving member extending through the shaft and adapted to transmit the power of the motor from one end of the armature shaft to the engine part at the other end thereof.
3. In combination with an electric starting motor whose armature shaft is hollow from end to end and power-transmitting means interposed between such armature shaft and a part of the engine to be started, said means including a driving shaft extending through the armature shaft and operatively connected therewith, said driving shaft being mounted for rotarial movement with the armature shaft and longitudinal movement with respect thereto.
4. In combination with an electric starting motor whose armature shaft is hollow from end to end and transmission means interposed between such armature shaft and a part of the engine to be started and having a power transmitting portion extending through and supported by the shaft for rotarial movement therewith and longitudi-

dinal movement thereof and operatively connected at one end with the armature shaft and having at its other end a driving member adapted to operatively engage said engine part.

5. In combination with an electric starting motor whose armature shaft is hollow from end to end and power-transmitting means interposed between such armature shaft and a part of the engine to be started and extending on opposite sides of the motor, said means including a shaft extending through the armature shaft and operatively connected at one end to such armature shaft and adapted to transmit power through its length to the other end thereof.

6. In combination with an electric starting motor whose armature shaft is hollow from end to end and power-transmitting means interposed between such armature shaft and a part of the engine to be started and including a rotatable member extending through the shaft and operatively connected therewith at one side of the motor and provided at the other side thereof with a driving member adapted to engage said engine part.

7. In combination with an electric starting motor whose armature shaft is hollow from end to end and power-transmitting means interposed between such armature shaft and a part of the engine to be started, said means including a driving portion extending through the shaft and adapted to transmit the power of the motor from one end of the armature shaft to the engine part at the other end thereof and a yielding driving connection between said portion and the armature shaft.

8. In combination with an electric starting motor whose armature shaft is hollow from end to end and power-transmitting means interposed between such armature shaft and a part of the engine to be started, said means including a shaft extending through the armature shaft and extending therebeyond, and having on one end a driving member adapted to engage and drive such engine part, and a spring driving connection between the armature shaft and the other end of the other shaft.

9. In combination with an electric starting motor whose armature shaft is hollow from end to end, a shaft arranged within the armature shaft and operatively connected therewith, and a driving member arranged on the second-named shaft and adapted, as a result of the rotation of the motor, to be automatically engaged with a part of the engine to be started.

10. In combination with an electric starting motor whose armature shaft is hollow from end to end, a shaft arranged within the armature shaft and operatively connected therewith at one end, and a driving mem-

ber arranged on the other end of the second named shaft and adapted, as a result of the rotation of the motor, to be automatically engaged with a part of the engine to be started.

11. In combination with an electric starting motor whose armature shaft is hollow from end to end and power-transmitting means interposed between such armature shaft and a part of the engine to be started, said means including a member passing through the armature shaft and at one end operatively connected therewith, and a member at the other end of the first-named member arranged to engage and drive said engine part.

12. In combination with an electric starting motor whose armature shaft is hollow from end to end and power-transmitting means interposed between such armature shaft and a part of the engine to be started and normally disengaged therefrom, said means including a driving shaft passing through the armature shaft and at one end operatively connected therewith, and a pinion arranged on the other end of and rotarily driven by the driving shaft and adapted to engage and drive said engine part.

13. In combination with an electric starting motor whose armature shaft is hollow from end to end and power-transmitting means interposed between such armature shaft and a part of the engine to be started and normally disengaged therefrom, said means including a screw-threaded member operatively connected with the armature shaft, and a pinion screw-threaded on said member and capable of longitudinal and rotary movements, whereby when said member is rotated the pinion will first be advanced longitudinally into mesh with the engine part and then rotated to rotate said part.

14. In combination with an electric starting motor having an armature provided with a shaft which is hollow from end to end, a rotatable member arranged within such shaft and operatively connected therewith, and a driving member mounted on such rotatable member for rotary movement therewith and longitudinal movement with respect to the armature shaft.

15. In combination with an electric starting motor having an armature provided with a shaft which is hollow from end to end, a rotatable member arranged within such shaft and operatively connected therewith at one end, and a driving member mounted on such rotatable member at the other end thereof for rotary movement therewith and longitudinal movement thereof.

16. In combination with an electric starting motor whose armature is provided with a shaft hollow from end to end, a rotatable shaft passing through the hollow shaft and

operatively connected therewith, and a driving member mounted on such second-mentioned shaft for longitudinal movement thereof and rotary movement therewith.

17. In combination with an electric starting motor whose armature is provided with a shaft hollow from end to end, a rotatable shaft passing through the hollow shaft and operatively connected therewith, such rotatable shaft having a screw-threaded portion projecting beyond one end of the hollow shaft, and a pinion mounted on such portion for longitudinal movement thereof and rotary movement therewith.

18. In combination with an electric starting motor whose armature is provided with a hollow shaft, a rotatable shaft passing through the hollow shaft and extending beyond the opposite ends thereof, means for operatively connecting one end of the rotatable shaft to the hollow shaft, the other end projecting beyond the hollow shaft having a screw threaded portion, and a driving member mounted on such portion for longitudinal movement thereof and rotary movement therewith.

19. In combination with an electric starting motor having a hollow armature shaft, a rotatable shaft having screw threads at one end and arranged within and extending beyond the ends of the armature shaft, and a pinion mounted on the screw-threaded portion of the rotatable shaft for rotary movement therewith and longitudinal movement thereof, said two shafts being operatively connected.

20. In combination with an electric starting motor having a hollow armature shaft, a rotatable shaft having screw threads at one end and arranged within and extending beyond the ends of the armature shaft, a pinion mounted on the screw-threaded portion of the rotatable shaft for rotary movement therewith and longitudinal movement thereof, and a resilient driving connection between the two shafts.

21. In combination with an electric starting motor having a hollow armature shaft, a rotatable shaft having screw threads at one end arranged within and extending beyond the ends of the armature shaft, a pinion mounted on the screw-threaded portion of the rotatable shaft for rotary movement therewith and longitudinal movement thereof, and a spring forming a driving connection between the two shafts.

22. In combination with an electric starting motor having a hollow armature shaft, a rotatable shaft having screw threads at one end arranged within and extending beyond the ends of the armature shaft, a pinion mounted on the screw-threaded portion of the rotatable shaft for rotary movement therewith and longitudinal movement thereof, and a spring connecting between the

armature shaft and the end of the rotatable shaft opposite its screw-threaded end.

23. In a device of the character described, the combination with an electric motor, of 5 a rotatable screw shaft supported thereby, a pinion mounted thereon toward one end thereof for rotary movement therewith and longitudinal movement thereof, and a driving connection between the motor and other 10 end of the screw shaft, said pinion and driving connection being located at opposite ends of the motor.

24. In a device of the character described, the combination with an electric motor, of 15 a rotatable screw shaft supported thereby, a pinion mounted thereon toward one end thereof for rotary movement therewith and longitudinal movement thereof, and a driving connection between the motor and other 20 end of the screw shaft, said motor being located intermediate the pinion and the driving connection.

25. In a device of the character described, the combination with an electric motor, of 25 a rotatable screw shaft supported thereby, a pinion mounted thereon toward one end thereof for rotary movement therewith and longitudinal movement thereof, and a driving connection between the motor and other 30 end of the screw shaft, said pinion and driving connection being located at opposite ends of the motor and said shaft having a yielding longitudinal movement.

26. In a device of the character described, 35 the combination with an electric motor, of a rotatable screw shaft supported thereby, a pinion mounted thereon toward one end thereof for rotary movement therewith and longitudinal movement thereof, and a yielding driving connection including a spring 40 between the motor and other end of the screw shaft, said pinion and driving connection being located at opposite ends of the motor and the shaft having a longitudinal 45 movement against the tension of said spring.

27. In combination with an electric starting motor and its armature having a hollow center, a driving head secured to such armature and located at a point adjacent the motor, 50 a rotatable shaft located in said hollow center and extending therefrom, a resilient driving connection between said head and shaft, and a driving member mounted on such shaft for rotary movement therewith 55 and longitudinal movement therof.

28. In combination with an electric starting motor and its armature having a hollow center, a driving head secured to such armature and located at a point adjacent the motor, 60 a rotatable shaft located in said hollow center and extending therefrom, and having screw-threads on said extending portion, a spring-driving connection between said head and shaft, and a pinion mounted on 65 said screw threads for rotary move-

ment therewith and longitudinal movement thereof.

29. In combination with an electric starting motor and its armature which is provided with a shaft hollow from end to end, 70 a driving head secured to the armature, a rotatable shaft within said hollow shaft, a resilient driving connection between said head and rotatable shaft, and a driving member mounted on such shaft for rotary 75 movement therewith and longitudinal movement thereof.

30. In combination with an electric starting motor and its armature which is provided with a shaft hollow from end to end, 80 a driving head secured to the armature, a rotatable shaft within said hollow shaft, a coiled spring anchored at its ends respectively to said head and rotatable shaft and forming a resilient driving connection 85 between them, and a driving member mounted on such shaft for rotary movement therewith and longitudinal movement thereof.

31. In combination with an electric starting motor and its armature which is provided with a shaft hollow from end to end, 90 a driving head secured to the armature, a rotatable shaft within said hollow shaft, and having a screw-threaded portion, a driving connection consisting of a coiled spring 95 connected respectively with said head and shaft, and a pinion mounted on said screw-threaded portion for rotary movement therewith and longitudinal movement thereof.

32. An engine-starter having, in combination, an electric motor provided with a hollow armature-shaft; a drive-shaft extending entirely through and rotatable within the armature-shaft; means providing a driving-connection between the armature-shaft 100 and one end of the drive-shaft; and means for connecting the other end of the drive-shaft with the engine.

33. An engine-starter having, in combination, an electric motor provided with a hollow armature-shaft; a drive-shaft extending entirely through and rotatable within the armature-shaft; means providing a driving-connection between the armature-shaft and one end of the drive-shaft; and a shiftable 110 pinion for connecting the other end of the drive-shaft with the engine.

34. An engine-starter having, in combination, an electric motor provided with a hollow armature-shaft; a drive-shaft extending through and rotatable within the armature-shaft; a yielding connection between the armature-shaft and one end of the drive shaft; and means for connecting the other end of the drive-shaft with the engine. 120

35. An engine-starter having, in combination, an electric motor provided with a hollow armature-shaft; a drive-shaft extending through and rotatable within the armature-shaft; a spring connecting the armature- 125

shaft with one end of the drive-shaft; and positively acting means for connecting the other end of the drive-shaft with the engine.

36. In an engine starter, the combination, 5 with a hollow driving shaft, of power transmission means therefrom to a member of the engine to be started, such means comprising a driven shaft extending entirely through the hollow shaft, a driving connection between two adjacent ends of the two shafts, and a driving connection mounted on the other end of the driven shaft and adapted to coöperate with the engine member.

37. In an engine starter, the combination, 15 with a hollow driving shaft, of power transmission means therefrom to a member of the engine to be started, such means comprising a driven shaft extending entirely through the hollow shaft, a yielding driving connection between two adjacent ends of the two shafts, and a driving connection mounted on the other end of the driven shaft and adapted to coöperate with the engine member.

20 38. In an engine starter, the combination,

with a hollow driving shaft, of power transmission means therefrom to a member of the engine to be started, such means comprising a driven shaft extending entirely through the hollow shaft, a coiled spring connected at its ends to two adjacent ends of the two shafts and acting as a driving connection between them, and a driving connection mounted on the other end of the driven shaft and adapted to coöperate with the 35 engine member.

39. In an engine starter, the combination, 40 with a hollow driving shaft, of power transmission means therefrom to a member of the engine to be started, such means comprising a driven shaft extending entirely through the hollow shaft, driving heads secured to two adjacent ends of the two shafts, a coiled driving spring encircling the driven shaft and anchored at its ends to the two heads 45 respectively, and a driving connection mounted on the other end of the driven shaft and adapted to coöperate with the engine member.

VINCENT BENDIX.
